UNITED STATES PATENT OFFICE

HARRY M. WHITMAN AND LEWIS A. MARTIN, OF CANTON, PENNSYLVANIA, GAIN
MARTIN ASSIGNEE TO SAID WHITMAN

ADDRESSING-MACHINE.

1,085,394

Specification of Letters Patent. Patented Jan. 27, 1914.

Application filed November 23, 1912. Serial No. 733,152.

To all whom it may concern:

Be it known that we, HARRY M. WHITMAN and LEWIS A. MARTIN, citizens of the United States, residing at Canton, in the county of Bradford, State of Pennsylvania, have invented a new and useful Addressing-Machine, of which the following is a specification.

This invention relates to machines for addressing newspaper wrappers, envelopes, and the like, and one of its objects is to provide a machine made up of few parts, which is strong and durable and by means of which newspapers or circulars may be rapidly and easily addressed without requiring the employment of skilled labor.

A particular object of the invention is to provide improved means for feeding a slug or Linotype from a holding or feeding galley to a working point and then moving the same into a receiving galley after the address has been imprinted upon the paper or the like, and to provide, in conjunction with such feeding means, means for adjusting the feeding means to slugs of different thicknesses and to one or more slugs.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

In said drawings—Figure 1 is a front elevation of the machine. Fig. 2 is a bottom plan view of a portion of the machine and illustrating, by dotted lines, the movements of the several parts. Fig. 3 is a vertical sectional view taken transversely of the machine and adjacent the slug feeding slide. Fig. 4 is an enlarged plan view of the slug feeding slide and the adjacent parts. Fig. 5 is a similar view showing the slide adjusted to another position. Fig. 6 is a detail view showing, in elevation, the trip and the rest forming a part of the hammer operating mechanism. Fig. 7 is a

section on the line A—B Fig. 4. Fig. 8 is a section on the line C—D Fig. 2.

Referring to the figures by characters of reference 1 designates a base plate or table supported upon suitable legs 2. A stationary shaft 2' is supported by the legs and has a treadle 3 adapted to swing thereon and which is held normally in a predetermined position by means of a spring 3' which is coiled about the shaft 2' and is secured at one end to said shaft and at its other end to the treadle. The upper end of the treadle is connected, in any suitable manner, to the lower end of a lever 4 fulcrumed upon a standard 4' which connects the table 1 to the shaft 2'. The upper end of the lever 4 is connected by a link 5, with a slide 6 mounted transversely in the table or base plate 1 and movable upon guiding ribs 7 on the under side of the base plate or table, as shown particularly in Fig. 2. The slide 6 is so shaped as to extend upward through a transverse slot 8 in the table and is provided with an upper portion 9 which rides upon and between guiding ribs 10 on the upper side of the table. At its front end this upper portion 9 of the slide is constructed with an enlarged head 11 which is adapted to move across the end of a galley 12 which for convenience we will designate the holding or feeding galley. The front end of the head 11 presents a square shoulder 13 which is adapted to engage the end of a slug at the end of the galley and push the same toward the front of the table into position in front of a slide 14 and between 90 the said slide and a receiving galley 15 at which point the hammer 16 is adapted to strike the newspaper placed over the slug and under the end of a holding spring 17 secured on the top of the slide 14, as will be understood. The slugs of type within the feeding galley 12 are moved progressively toward the path of movement of the feeding slide 9 so as to be projected into position in front of the pusher head 11 on the said slide by a follower 18 which is slidably mounted on a guide rod 19 secured on the base plate parallel with and adjacent to the side of the feeding galley and is held against the back end of the body of type and drawn toward 108 the front or open end of the galley by a weight 20 suspended by a cable or other flexible connection 21 which passes over

pulleys 22 and 23 on the table and has its upper end secured to the follower. The front pulley 23 is arranged adjacent the front end of the galley so that as the weight 5 20 descends the pull exerted thereby on the follower will be toward the open end of the galley and consequently the type will be moved over the bottom of the galley toward the open end of the same and will be successively placed in position to be engaged 10 by the pusher head 11. In order to accommodate slugs of different thicknesses, the feeding slide is provided with a forwardly projecting finger or stop 24 at the inner end 15 of which is provided a lateral arm 25 adapted to slide transversely upon the feeding slide 9 and thereby be moved toward and from a rib 26 upstanding from the edge of the pusher head 11. The finger 24 projects 20 beyond the end or shoulder 13, and it will be understood, of course, that if the finger is directly against the rib 26 the space between the side of the finger and the end of the feeding galley will be just equal to the 25 thickness of the said rib and this rib is equal in thickness to one line of type so that when the parts are in the position shown in Fig. 4, a single line of type will be carried across the table into position to be struck 30 by the hammer 16. When the slide is in its rearmost position the shoulder 13 will be back of the side of the feeding galley so that the follower may push the type in the said galley toward the front or open end of the 35 galley a distance equal to the space between the end of the galley and the side of the finger 24 so that if the said finger be moved from the rib 26 more than one line of type may be fed against the said finger into position 40 to be actuated by the shoulder 13 or end of the pusher head. It will thus be seen that by adjusting the finger 24 toward or from the rib 26, slugs of different widths and carrying one or more lines of type according to the length of the address to be 45 printed may be readily utilized in our machine. In order to adjust the slide 25 with its finger 24 as may be necessary to accommodate slugs of different widths, we employ 50 a hand lever 27 which is fulcrumed at 28 on the upper side of the feeding slide immediately adjacent the arm or slide 25 and is provided at its front end with a finger or point 29 extending between two pins or lugs 55 30 rising from the upper side of the said arm 25. As this hand lever is swung to one side or the other the finger 29 will act against one of the pins 30 so as to move the arm 25 transversely of the feeding slide and thereby adjust the finger 24 to the desired 60 position and the parts may be held in the adjusted position by means of the pin or locking pawl 31 carried by the hand lever near the rear end of the same and engaging notches 32 in a segmental holding bar or

plate 33 at the rear end of the feeding slide 9, as clearly shown.

The lateral arm 25 is held to the feeding slide by means of a rib 34 and a lug or plate 35 which is secured upon the upper 70 side of the slide at the front end of the same, the said rib 34 and the lug or plate 35 being downwardly beveled on their opposed edges, and the arm 25 having beveled sides, as indicated at 36, whereby the 75 said arm will be fitted to the rib and the plate by a dove-tailed formation which will permit the arm to easily slide laterally but will prevent all rising movement of the same. The plate 35 is secured to the slide 80 9 by screws or similar fastenings 37 whereby the parts may be readily assembled and accurate fitting of the same may be attained.

The galleys are held firmly upon the table by being fitted between ribs 38 and any 85 convenient construction may be employed to lock the galleys to the said ribs while they are in use, the forward or receiving galley being placed against a slight shoulder 39 on the table so that the bottom of the said 90 galley will lie flush with that portion of the table upon which type is supported while a newspaper is being addressed so that after the address has been printed type may be pushed readily into the galley, as will be 95 understood. In order to prevent the type falling after it has been pushed into the receiving galley or during its movement into the said galley, a spring holding finger 40 is secured on the table at the front side of 100 the same and projects over the table in position to bear against the end of the slug while it is being pushed into the receiving galley and to engage behind the type after it has entered the galley.

The slide 14 moves within suitable guides upon the table and depends through a slot 41 therein and is provided on its under side with a depending lug or projection 42, said lug being connected by a link 43, with a 110 coiled spring 44 connected, as at 45, to the bottom of the table 1, this spring serving to pull constantly on the lug 42. A bell crank lever 46 is fulcrumed on the under side of the table and has one arm adapted to bear against the outer edge of the lug 42 and its other arm connected by a link 47 with the under side of the slide 6, as clearly shown in Fig. 2. When the treadle 3 is manipulated, to move the slide 6 toward the front 115 side of the table and thereby feed type into position in front of the slide 14 the bell crank lever 46 is actuated through the link 47 so as to swing the forwardly extending arm of the lever away from the lug 42, as 120 shown by one set of dotted lines in Fig. 2. On the reverse movement of the treadle, the angle lever will be swung in the opposite direction so as to carry the said forwardly 125 projecting arm against the lug 42 so that 130

the continued movement of the treadle will cause the said arm to bear against the said lug and thereby push the slide 14 longitudinally of the table, and thereby carry the type from which the address has just been printed toward and into the receiving galley. This action will be in opposition to the spring 44 so that when the treadle again swings to move the slide 6 forward the said spring 44 will draw upon the lug 42 and consequently return the slide 14 to its position of rest. In Fig. 2, we have indicated the movement of the parts by dotted lines, the lighter dotted lines showing the position of the parts when the slide 6 is in its forward position, while the heavier dotted lines show the parts when the said slide is in its rearward position, the full lines showing the intermediate position when the slide 14 is at rest and the slide 6 is still moving rearward.

The hammer 16 is operated from the feeding slide 9 in the manner and by mechanism which we will now describe.

The hammer is secured to and carried by the free front end of a forwardly extending arm 51 of an angle lever which is fulcrumed upon a bracket 52 rising from the table. The rear arm 53 of the angle lever projects upward from the fulcrum of the same and carries at its upper end a stud 54 which plays in a slot 55 at the upper end of a link 56 which has its lower end pivoted to the side of the feeding slide at the rear end of the same. A spring 57 is coiled around the fulcrum of the angle lever 51-53 so as to aid in the operation of the said lever, as will be presently stated. On the side of the arm 51 is a lug 58 which is adapted to rest upon a trip 59 pivotally mounted on a suitable stationary post 60 rising from the table and controlled by a coil spring 61 around the post with its ends attached to the base of the same and to the trip respectively. The base of the post 60 is provided with a series of openings or sockets 62 in which the ends of the spring 61 may be fitted so as to vary the tension of the spring, as will be understood, and from the under side of the trip 59 depend pins 62, the forward pin being adapted to impinge against a pin 63 rising from the base of the post so as to limit the forward movement of the trip. The rear pin 62 is adapted to be engaged by a vibrating hook 64, carried by the feeding slide 9, on the rearward movement of the said slide so that the trip will be rotated against the tension of the spring 61 and thereby moved from under the lug 58 on the arm 51 whereupon the hammer will be at once thrown against the paper placed over the address through the action of the spring 57. The impact of the hammer against the paper will cause an impression of the address to be made on the paper, as will be readily understood.

stood, and in order to prevent injury to the type the under side or working face of the hammer is provided with a cushion 65 of leather, rubber or other suitable material. The vibrating hook 64 is pivotally secured upon the slide 9 near the rear end of the same and is thrown normally toward the trip by a spring 66 coiled around the pivot of the hook and secured to the same and bearing against the side of the hook. In order to prevent the hook being thrown beyond the position where it will engage the trip after it has released the trip during the operation of the machine, a stop 67 is secured upon the slide and projects upward therefrom into position to be engaged by the side of the hook, as will be readily understood on reference to the drawings. Upon reference to Fig. 3 it will be observed that the trip 59 has an upstanding portion presenting a horizontal shoulder 68 with a vertical shoulder 69 extending down to a horizontal ledge 70. When the hammer is in its raised position the lug 58 thereon rests upon the shoulder 68 of the trip just in rear of the vertical shoulder 69 thereof so that it will be held in this raised position by the trip. On the rearward movement of the feeding slide 9, the shoulder 71 of the hook 64 engages the rearward pin 62 of the trip and consequently pulls upon the trip so as to rotate the same against the tension of the spring 61 and thereby swings the upstanding portion of the trip from under the lug 58 whereupon the hammer will be thrown downward through the action of the spring 57 and its own weight, as will be readily understood, the lug 58 assuming a position in front of and against the vertical shoulder 69 whereby the trip will be held in its rearward position against the tension of the spring 61. On the forward movement of the feeding slide, the curved face 72 of the hook 64 will ride against the depending pin 62 of the trip and will be thereby vibrated on its pivot against the tension of the spring 66 so that as soon as the hook has cleared the pin 62 the said spring will throw the hook outward so that the shoulder 71 thereof will again be in position to engage the pin 62 on the next rearward movement of the slide. The rearward movement of the slide, with the hook in engagement with the depending pin, will tend to retard the hook so that the same will drag and this dragging will vibrate the hook upon its pivot in such a manner that the instant the hammer drops, the hook will clear the pin 62 and will then move rearward free of the same. The coil spring 61 will then at once throw the trip forward so that the shoulder 69 will bear against the lug 58 and the hammer and the trip will remain in this position until the upper end of the slot 55 engages the stud 54 whereupon the rearward movement of the

feeding slide will be communicated to the angle lever 51—53 so as to vibrate the same against the tension of the spring 57 and raise the hammer. The spring 61 will then be free to act and will rotate the trip 59 so as to bring the shoulder 68 under the lug 58 and consequently support the hammer in its raised position until it is again released through the operation of the feeding slide 10 and the hook 64, as previously described. The forward movement or rotation of the trip will be limited by the front pin 62 impinging against the stop pin 63 so as to hold the stop in proper position to support the hammer.

In order to properly limit the movement of the slide 14, so that on its reverse travel it will not carry its front end beyond the position in which it will properly support the type for use in addressing the paper, we employ stops 73 and 74 the stop 73 consisting of a set screw mounted in a lug 75 on the slide and adapted to bear against the stop 74 which is mounted in the table, as will be readily understood. By adjusting the set screw 73 so that it will properly come into contact with stop 74, at the rearward movement of the slide, the said slide will be caused to come to rest at such a point that its front end will lie in the same plane with the front side of a guide 76 on the table. As the feeding slide moves forward over the table the type engaged by the front end or shoulder 13 of the pusher head and the side 35 of the finger 24 will be moved bodily over the table along the side of the guide 76 and be supported between the end of the slide 14 and the side of the finger 24.

From the foregoing description, taken in connection with the accompanying drawings, it will be seen that we have provided by a very compactly arranged machine by means of which newspapers or other mail matter may be readily addressed and in which the parts are of simple construction so that they are not liable to get out of order and will be durable and efficient. The operator will sit in front of the machine with his foot upon the operating treadle and place 40 the paper or circular under the spring 17 carried by the slide 14 and will operate the machine by swinging the treadle back and forth, as will be understood. As each paper is addressed it will be withdrawn and another paper substituted and the treadle vibrated so as to operate the parts in the manner herein described, as will be readily understood. The addresses will be arranged within the feeding galley and the follower 50 placed against the back end of the body of addresses so that the weight connected with the follower will draw the same continuously forward as a slug or address is removed from the feeding galley to the receiving galley until all the slugs in the feeding galley

have been used. The empty galley may be removed and a filled galley substituted therefor in a very short period of time. The machine will preferably be manipulated so that single line addresses will be placed in one galley and double line addresses in another 70 galley, while three-line addresses may be placed in a third galley inasmuch as this arrangement will obviate any necessity of adjustment of the feeding slide during the 75 operation of the machine, but it will, of course, be within the privilege of the operator to arrange the addresses promiscuously and adjust the feeding slide to the width of the addresses as they are severally presented 80 to the slide but this latter arrangement will obviously reduce the speed at which the machine may be operated.

A guide rod 77 may be extended longitudinally on the table and between the ribs 38 85 and the slide 14, this rod serving as a guide for an inking roller which is adapted to be moved by hand over the slugs in the feeding galley.

What is claimed is:—

1. The combination of a feeding galley, a slide adapted to engage type at the end of the said galley and move the same transversely of the galley to a position of rest, a hammer adapted to deliver a blow upon the 95 said type while in said position of rest, a slide adapted to move the type away from the said position of rest, and means controlled by said first mentioned slide to operate the hammer and the slide by which the type is removed from its position of rest.

2. The combination of a feeding galley, a slide movable across the end of the said galley and provided at its end adjacent the galley with an upstanding rib, a finger projecting from the end of the said slide and having a lateral arm at its inner end slidably mounted on the upper side of the slide whereby the finger may be moved toward and from the said rib, pins rising from the 110 said arm, and a lever fulcrumed upon the slide adjacent the said arm and provided with a finger engaging between the said pins.

3. The combination of a hammer, a trip normally supporting the said hammer in a 115 raised position, a type feeding slide adapted to feed type to a position under the hammer, and means actuated by the said slide to operate the trip and release the hammer and to return the hammer to its raised position.

4. The combination of a hammer, a trip normally supporting the hammer in its raised position, a type feeding slide adapted to feed type to a position under the hammer, and means actuated by the slide for successively operating the trip to release the hammer, for again raising the hammer, and for operating the trip to again engage the hammer in its raised position.

5. In an addressing machine, the combination of a supporting table, a pair of type feeding slides moving at right angles to each other, operating mechanism connected to one of the said slides, an angle lever connected with the said slide, a lug depending from the other slide and bearing against the said angle lever, and a spring secured to the table and acting on the said lug in opposition to the angle lever.

6. The combination of a supporting table, a pair of slides mounted thereon and moving in intersecting paths, operating mechanism connected to one of the said slides, an angle lever fulcrumed on the table and connected with the said last mentioned slide, a lug depending from the other slide and bearing against the said angle lever, and a spring secured to the table and to the lug for holding the lug yieldingly against the lever.

7. The combination of a type feeding slide, a hammer disposed at one side of the slide, a trip normally supporting the hammer in a position of rest, a hook carried by the slide and adapted to engage the trip to release the hammer, and a connection between the slide and the hammer to return the same to its position of rest.

8. The combination of a type feeding slide, a rotary trip arranged at one side of the slide and having depending pins, a hook carried by the slide and adapted to engage one of the said pins to rotate the trip, a spring coiled around the said trip and secured thereto to rotate the same in a direction opposite to the rotation imparted thereto by the slide, a stop arranged to limit the movement of the trip under the influence of the spring, a hammer having a lug normally resting on the said trip and adapted to clear the same when the slide actuates the trip, and a connection between the slide and the hammer to raise the hammer.

9. The combination of a type feeding slide, a rotary trip arranged at the side of the slide and having an upstanding portion and provided with depending pins in advance of the said upstanding portion, a

Spring acting on the said trip to throw the said upstanding portion forward, a stop 50 adapted to be engaged by one of the depending pins to limit the forward movement of the said upstanding portion of the trip, a hook carried by the slide and adapted to engage the other depending pin, an angle 55 lever having forwardly projecting and upstanding arms and carrying a hammer on its forwardly projecting arm and provided with a lug on said arm adapted to normally rest on the upstanding portion of the trip, and a link pivoted to the slide and provided at its upper end with a longitudinal slot engaging a stud on the upstanding arm of the angle lever.

10. The combination with a feeding galley, of a slide movable across the end of the galley and constituting means for engaging a type and shifting it laterally from the end of the galley, a stop finger carried by the slide and constituting means for limiting a 60 type in its movement from the galley and into the path of the slide, means for automatically projecting a type from the galley and into the path of the slide and against the finger, and means carried by the slide for 65 adjusting said finger upon the slide and toward or from the galley.

11. The combination with a feeding galley, of a slide movable across the end of the galley, a finger projecting from the end of 70 said slide and having a lateral arm at its inner end slidably mounted on the slide whereby the finger may be moved toward and from the galley, and a lever fulcrumed on the slide and shiftable to move the arm 75 and finger relative to the slide and toward or from the galley.

In testimony that we claim the foregoing as our own, we have hereto affixed our signatures in the presence of two witnesses.

HARRY M. WHITMAN.
LEWIS A. MARTIN.
